UNITED STATES PATENT OFFICE.

EARL H. SHERBONDY, OF CLEVELAND, OHIO.

TURBINE-CASING.

1,310,674.

Specification of Letters Patent. Patented July 22, 1919.

Application filed April 2, 1918. Serial No. 226,289.

To all whom it may concern:

Be it known that I, EARL H. SHERBONDY, a citizen of the United States, residing at Cleveland, in the county of Cuyahoga and 5 State of Ohio, have invented certain new and useful Improvements in Turbine-Casings, of which the following is a specification.

This invention relates to a casing for a 10 fluid operated turbine. The main object of the invention is to provide a turbine casing of simple construction, which may be made of pieces that are stamped out of sheet metal, that can be readily assembled into a casing 15 unit.

The casing is of a type similar to the turbine casing shown in my co-pending application, Serial Number 224892, filed March 26, 1918.

20 The turbine used in connection with the casing is intended to be operated by the exhaust gases from an airplane engine and may be used to drive a centrifugal blower, as shown more particularly in my copending application, Serial Number 224356, filed March 14, 1918.

Another important object of the invention 30 is to design a casing that can be produced in large quantities. A sheet metal casing, once the dies are made, can obviously be produced in large quantities.

Other objects and advantages will appear as the description proceeds.

Referring now to the drawings, in which 35 similar reference characters indicate similar parts, Figure 1 is a side view, partly in section, of the casing; Fig. 2 is a top view, partly in section, taken at right angles to Fig. 1; Fig. 3 is a view of Fig. 1 looking 40 from the right; and Fig. 4 shows a slight modification.

The turbine casing consists of the main casing element C, which is of the curved, annular shape as shown in Fig. 1 and is 45 stamped out of sheet metal. A semi-circular section P is formed integral with the main casing element C during the stamping process.

Associated with said casing element C, 50 there is an annular diaphragm D, stamped out of sheet metal. Formed integral with the diaphragm D, is a semi-circular portion P'. The semi-circular portions P and P' have substantially the same radius and are 55 adapted to be fitted together to define an inlet pipe I, when the parts C and D are fitted

together, as shown in Fig. 1. The casing C and diaphragm D together define an inlet chamber 1, which chamber is in communication with the inlet pipe I. 60

Casing C and diaphragm D converge toward their inner ends and between said inner ends is located a series of nozzles 2 of any desired construction. These nozzles direct the gases onto the buckets 3 of the turbine 65 4.

Auxiliary casing elements A and A', generally annular in shape, are provided and are stamped out of sheet metal. Each of the auxiliary elements A and A' are formed 70 with semi-circular portions Q and Q', of the same radius, which portions are adapted to fit together to define an outlet pipe O.

One of the auxiliary casing elements such as A', is attached to the diaphragm D in any 75 suitable way, such as by the rivets 5. The elements A and A' are flanged to fit against one another as at point 6.

The other of the auxiliary casing elements, such as A, is provided with a flange 7, to 80 which flange is attached a back plate B, which plate extends inwardly from the flange 7 to a point at the inner edge of the buckets 3, being bent as shown to provide a curved path for the gases escaping from 85 the buckets 3.

Diaphragm D, casing elements A and A' and back plate B together define the outlet chamber 8, which chamber communicates 90 directly with the outlet pipe O.

The normal course of the gases is indicated by the arrows, the gases going into the inlet chamber 1 through the pipe P, passing through the buckets 3 into the outlet chamber 8 and thence out through the 95 outlet pipe O.

The parts P, P', Q and Q' may be provided with suitable flanges turned over at right angles for the attachment of the necessary inlet and exhaust pipes. 100

The diaphragm D, it should be noted, is positioned between the inlet pipe I and the outlet pipe O at right angles thereto, to define the inlet and outlet chambers 1 and 8 respectively. 105

In order to control the speed of the turbine, the diaphragm D may be provided with means to by-pass the gases directly from the chamber 1 to the chamber 8 without going through the turbine buckets 3. 110 This by-pass may consist of a valve 9, seated on a valve seat 10, which valve seat may be

pressed out of the diaphragm D and so made integral therewith. The valve 9 may be operated by any suitable means, such means being shown in my co-pending application, Serial Number 224894, filed March 26, 1918.

Fig. 1 shows inlet pipe I located at the side of the casing unit as a whole. It is obvious, however, that this inlet pipe I can 10 be located at the back of the casing and such a modification is shown in Fig. 4.

In this case, the pipe I' is pressed out and integral with the main casing element C'; diaphragm D', in this case, playing no part 15 in forming the inlet pipe. The diaphragm D' is attached to the main casing element C' at the point 11, by means of two annular flanges, one being formed on D' and the other being formed on C'. The diaphragm 20 D' may, as in Fig. 1, carry a valve for bypassing the gases, which, however, it is not thought necessary to show.

It should be noted that the elements for the casing may be readily stamped out of 25 sheet metal. This is an important feature of the invention because it permits a production of the casing unit in large quantities and does away with a lot of machining, brazing, welding and casting.

30 While I have illustrated two embodiments of my invention, it should be understood that the invention may be carried out in other ways and, therefore, the disclosure should be considered in an illustrative 35 sense and not in a limiting sense.

I claim:

1. In a turbine casing, a main casing ele-

ment and a diaphragm, the two said parts being stamped out of sheet metal to define an inlet chamber and to form a pipe, parts 40 of said pipe being integral, respectively, with said main casing element and said diaphragm.

2. The combination as claimed in claim 1, the said diaphragm having a valve seat 45 pressed out from it and integral therewith.

3. In a turbine casing, diaphragm, auxiliary casing elements associated therewith, the said parts being stamped out of sheet metal, said auxiliary casing elements having 50 parts pressed therefrom to form a pipe, the parts of said pipe being integral, respectively, with said auxiliary casing elements.

4. The combination as claimed in claim 3, the said diaphragm having a valve seat 55 pressed out from it and integral therewith.

5. The combination as claimed in claim 3, in combination with a back plate stamped out of sheet metal, the said diaphragm, auxiliary casing elements and back plate defining 60 an exhaust chamber in communication with said pipe.

6. A turbine casing comprising a main casing element and a diaphragm, parts of each being pressed out therefrom to form a 65 pipe, a back plate, auxiliary casing elements having parts pressed out therefrom to form a pipe, the said diaphragm being positioned between said pipes to define inlet and exhaust chambers. 70

7. The combination as claimed in claim 6, the parts being stamped out of sheet metal.

In testimony whereof I affix my signature.

EARL H. SHERBONDY.
